METHOD FOR REMOVING STAINS FROM
TEETH

Gilbert Dillie Laymon, Miami, Fla.

No Drawing. Application October 15, 1934,
Serial No. 748,427

2 Claims. (Cl. 167—93)

This invention relates to the method and means for removing stains from teeth. It is known that the teeth are normally covered with a persistent film or plaque of mucin and which film is the recipient of the various objectionable stains which it is the purpose of the present invention to remove.

The difficulty which is customarily experienced in removing certain types of stains, for example, that of nicotine, is due to the fact that the detergent action of ordinary stain removers is expended solely at the surface of the mucin film, while the stain has penetrated into the film to a relatively great depth, that is to say, to a depth not reached by the detergent.

One of the objects of the present invention is the provision of a stain remover which shall penetrate the mucin film at least to the depth of the stain regardless of how far the latter may have been absorbed by the film.

Another object of the invention is to provide a stain remover comprising complementary substances, separately applied, the first of which is of deep penetrable nature with respect to the mucin plaque so as to sink in at least as far as the stain to be removed, and the second substance being reactive with respect to the first so that when applied to the film subsequent to the application of the first substance, a chemical action occurs in situ throughout the depth of the stain, which not only disintegrates the mucin film through the kinetics of the reaction, but at the same time decolors and obliterates the stains probably through oxidation.

More specifically, the object of my invention is to provide a stain remover in the form of two liquids having the co-operative properties above related, one being tincture of iodine which is applied to the mucin plaque and readily absorbed thereby to the entire depth of said plaque, the other being sodium thiosulphate which is also freely absorbed throughout the depth of the film and combines with the iodine in a reaction which decolors the stain and loosens the film.

A preferred and practical formula for my invention is as follows:

Solution No. 1—Iodine 3.3%

Solution No. 2—Sodium thiosulphate 5%

The above proportions are capable of being varied within wide limits without vitiating the function and effect of the invention.

It is a common expedient to stain the teeth with iodine preparatory to cleansing them in various ways, the iodine being merely a disclosing solution showing up by its color the areas where the mucin plaque still persists and by the absence of color those areas from which the mucin plaque has been removed. As has been stated, the mucin film is quite persistent and measures which have heretofore been used to remove stains have been

largely with the assistance of mechanical detergents and harmful to the teeth.

The iodine in the formula of the present invention not only plays the role of a disclosing agent, but as stated, it becomes a concomitant of the reaction by which the film is loosened and the stain decolorized.

After the application of the sodium thiosulphate to the iodine stained film, and the complete disappearance of the color of the iodine as well as the stain, the mucin film is readily removed by the use of the tooth brush.

The principle by which the stain remover acts has not been positively ascertained, but it is believed to be a phenomenon of electronic re-arrangement taking place in the combining substances during the period of their reaction.

In bringing the sodium thiosulphate and iodine together the resulting reaction may be represented by the following equation:

The process represented above is an oxidation-reduction process.

It happens that neutral iodine, that is, iodine of zero valence having the same number of negative charges (electrons) as it has positive charges, is colored a purplish color and its solutions are similarly colored. However, iodine that has gained an electron, and therefore has a minus one valence, is colorless, and its solutions are generally colorless. In the above reaction all of the iodine 2 (zero valence) has been changed to I⁻ (minus one valence) and consequently the color is lost.

In the above formulae and those that follow:

+ represents excess of one positive charge.

— represents excess of one negative charge (electron).

0 represents a balanced condition (just as many negative as positive charges).

Writing the equation with especial reference to the electron movements, we have:

(b) $\text{S}_2\text{O}_3 - + 2\text{Na}^+ \rightleftharpoons \text{Na}_2\text{S}_2\text{O}_3$ derived from (e)

(c) $2\text{I}^0 + 2\text{Na}^+ \rightleftharpoons 2\text{NaI}$

According to the theory on which the above equations are based, when a substance is oxi-

- dized it has lost electrons, and when it is reduced it has gained electrons. In general the oxidation of colored substances results in the destruction of the colored structures to some extent.
- 5 Sometimes this occurs in reduction through rearrangement.
- The destruction of the colors on the teeth is probably due to the oxidation of some organic colored materials.
- 10 The iodine may be destroying the color stains through oxidation and then the excess iodine applied may be bleached out by means of the sodium thiosulphate.
- 15 While I have in the above description disclosed what I believe to be a preferred and practical embodiment of my invention, it will be understood that the details of proportion and the technic involved in the application of the stain remover to the teeth are merely by way of example and not to be construed as limiting the scope 20 of the invention as claimed.

What I claim is:

1. Method of removing stains from teeth comprising impregnating the mucin film to a depth at least as great as the objective stain with an iodine solution, and treating the thus impregnated film with a solution of sodium thiosulphate whereby the kinetic as well as the chemical decoloring reaction of the substances is produced in situ in all regions of the objective stain. 5
2. Method of removing stains from teeth comprising impregnating the mucin film to a depth at least as great as the objective stain with a solution of iodine of substantially 3.3 percent strength, and treating the thus impregnated film with a sodium thiosulphate solution with approximately 5 percent strength, whereby the kinetic as well as the decoloring reaction of these substances is produced in situ in all regions of the objective stain. 10 15
